COMPRESSOR PISTON OR THE LIKE

Burton S. Aikman, Milwaukee, Wis., assignor to
 National Brake & Electric Company, Milwaukee,
 Wis., a corporation of Wisconsin

Application May 6, 1932. Serial No. 609,652

19 Claims. (Cl. 230—221)

This application is a continuation in part of my co-pending application Serial No. 443,317, filed April 11, 1930, which relates to a method of and means for compressing gases and which disclosed, 5 by way of illustration only, an air compressor capable of efficient operation at high speed without overheating. As more clearly pointed out in my copending application but which is mentioned here for emphasis, a number of factors are present in my compressor which contribute to this 10 high efficiency, among them being the intake valve construction, which is simple, of exceeding rapidity of operation, providing a large inlet opening, with rapid opening and closing to the full extent in a minute fraction of the cycle of operation. Another feature is the unusually small 15 clearance space and the extremely short passage between the valve and the interior of the cylinder. Another feature is the character of the lubricating 20 system, no appreciable oil being passed by the piston and hence, fouling of the discharge valve being prevented, with consequent minimum leakage of the discharge check valve. Due to non-interference of the lubrication requirements with 25 the valve action, the valves—that is, both the intake and the discharge valves—stay tight, and the aforesaid high efficiency may be maintained over long periods of use. Another feature is the novel 30 separation of the two functions of a trunk piston, and a thermal separation of the two parts of the trunk piston and the cooperating cylinder, extremely light weight reciprocating parts, together with other features, for the specific details of 35 which reference may be had to the disclosure in my copending application.

The present invention is principally concerned with the construction and arrangement of the piston and associated parts, and has for its primary purpose the provision of a piston structure 40 which is particularly adapted for high speed work and high volumetric efficiency. To this end there are a number of specific features of novelty in the structure to which attention will be more fully called later, but some of which may be referred to herein generally, namely, the double use of the piston ring groove clearance, the thermal separation of the two parts of the piston, the functioning of the piston structure in lubricating 45 the two parts of the compressor having different lubrication requirements, as by lubrication carriers or wipers carried by the piston structure and traveling between the two cylinder sections, or two cylinders, and other features 50 which will be apparent from the following de-

scription and attached drawings. The features which I have above enumerated I consider to be broadly new in a piston or the like and I intend to claim the same broadly.

Now, in order to acquaint those skilled in the art with the manner of constructing and operating a device embodying my invention, I shall describe, in connection with the accompanying drawings, a specific embodiment of the same.

In the accompanying drawings, in which like reference numerals refer to like parts throughout:

Figure 1 is a vertical longitudinal section through a compressor of my invention;

Figure 2 is a vertical elevation of my improved piston structure embodying the principles of the present invention and preferably utilized in the compressor illustrated in Figure 1;

Figure 3 is a longitudinal cross sectional view 75 through the piston shown in Figure 2 and corresponding to a section taken along the line 3—3 of Figure 2;

Figure 4 is a top plan view of the piston shown in Figure 2;

Figure 5 is a section taken along the line 5—5 80 of Figure 3;

Figure 6 is a fragmentary sectional view illustrating the position of the ring valve with respect to the piston during the compression stroke thereof;

Figure 7 is a similar fragmentary sectional view showing the position of the ring valve on the suction stroke of the piston;

Figure 8 shows a modified form of piston structure illustrating another method of lubrication 90 control and provided with means whereby excess oil is removed, partly mechanically and partly pneumatically, from the walls of the cylinder;

Figure 9 is a vertical sectional view taken along the line 9—9 of Figure 8;

Figure 10 is a cross section taken along the line 10—10 of Figure 8;

Figures 11 to 15, inclusive, illustrate various modified forms of the intake valve structure and the various modified forms of piston heads to 100 accommodate such intake valves; and

Figure 16 illustrates one form of step joint with which the ring valves may be provided.

The compressor in which the present invention is preferably employed is fully disclosed and claimed in my copending application identified above, but a brief reference will be made here to the compressor in order that the various details of my improved piston structure may be clearly understood and comprehended. It is to 105 110

be understood, of course, that air or gas compressors or the like constitute only one of many different installations in which the features of the present invention may be utilized.

5 Referring now more particularly to Figure 1, the main frame of the machine comprises a crank case and cylinder casting 1, the upper end of which comprises an integral cylinder section 2 and the lower part of which comprises a crank-
10 case section 3, integral with the cylinder 2 and having at its base a suitable oil sump 4, formed in an enlargement of the lower end of the crank case. The base 3 thus provides a relatively large volume of lubricating oil for operation of the
15 compressor over extended periods of time.

The case 3 is provided on one or both sides with a suitable hand hole 12 covered by a plate or cover member 13, this plate or cover member being removable for inspection of the lower end 20 of the connecting rod 14 and its bearing upon the crank pin 15. The crank shaft 16, which is adapted to be driven by any suitable means, is mounted as shown in bearings of the roller type 17 and 18, having their inner races mounted 25 upon the ends of the crank shaft 16 and their outer races mounted in circular end plates 19 and 20, which end plates are bolted by means of suitable flanges upon the ends of the crank case section 3. The end plates 19 and 20 are 30 suitably piloted into cylindrical bores in the end walls of the chamber 3 and are located angularly by means of dowel pins 22. Suitable packing, such as 24, is clamped between the plate and the crank casing to provide a tight joint. Cap 35 screws such as 25 extend through the flanges of the end plates and are threaded into the metal of the case 3 surrounding the cylindrical bores in the end walls. The crank shaft 16 is carefully counterbalanced against the weight of 40 the connecting rod and the connected piston. These parts are made as light as is consistent with the necessary strength and wearing qualities. The connecting rod 14 and the piston may 45 be made of lynite or other aluminum alloy, to reduce the weight and inertia of the same for high speed operation.

The connecting rod cap 32 is provided with a dipper, or oil thrower 33 for causing oil to be carried upwardly to lubricate the crank-shaft bearing, the connecting rod bearing and the piston with its guiding cylinder. The connecting rod is provided with lubricating passageways 34-34, to provide suitable lubrication for the connecting rod 14 and crank 15.

55 A suitable liner of bearing metal is provided on the connecting rod crank bearing according to known gas engine practice. The upper end of the connecting rod 14 has a liner or bushing 35 for receiving the wrist pin 36, which wrist pin is preferably gripped by the piston, being held therein by a cotter pin or the like, so that relative bearing motion between the pin 36 and the liner 35 occurs. Lubrication for this bearing is provided by an oil duct 37 extending through 60 the upper end of the connecting rod and through 65 the liner 35.

Piston construction

The piston 38 is a compound structure or it 70 may be considered as consisting of two functionally different parts. The lower part 39 of the piston 38 immediately adjacent the wrist pin 36 comprises a guiding member in the nature of a crosshead.

75 While the piston structure 38 is in reality a

trunk piston, forming both a guide member and a working or displacement member, the upper part or head portion 40, which performs the actual service of acting as a moving wall for the working chamber 42 of the cylinder, has substantially no guiding function, whereas the lower portion 39 has substantially no displacement function. In fact, the portion 39 does not enter the working chamber 42 of the cylinder 2. The head portion 40, which really becomes the 85 working piston or plunger, comprises a circular disc having the frusto-conical dome 43 adapted to enter the discharge passageway 44 of the compressor for minimizing the volumetric clearance. The passageway 44 is formed centrally of 90 the head 45 of the working cylinder 46. The bottom surface of the head 45 is carefully machined, as is the discharge passageway 44, and the cylinder head 40 and its boss 43 are likewise carefully machined, and the throw of the 95 crank is such that the head 40 approaches the cylinder head 45 almost to actual contact in order to minimize the loss in volumetric efficiency which any clearance at the end of the stroke entails.

100 As stated, the present invention is primarily concerned with the structure of the piston and associated parts. The working piston or head 40 is joined to the guiding portion 39 through a rigid crossed web connection 48, which supports 105 the head 40 substantially out of contact with the walls of the cylinder 46, the guiding action being secured mainly by the lower portion 39, and to some extent, if desired, by the oil wiper or oil distributor 47, which comprises a circular 110 disc or wall, cast integral with webs 48 and 49 joining the head portion 40 and with the lower portion 39. The disc 47 has, in one air cooled compressor which is of a capacity of 3.13 cubic feet per minute free air displacement at 1600 to 115 to 1700 R. P. M. with two inch bore and one inch stroke, a clearance of approximately .015 inch in the cylinder.

120 The lower surface of the disc 47 is dished in at the edges in order to provide a relatively sharp circular edge 47a tending to scrape inwardly and to carry downwardly any excess of lubricant which may lodge upon the inner wall of the guiding cylinder 2. The disc 47 is joined to the head or piston 40 by two thin webs crossing each other 125 at right angles forming a light but rigid connection 49 between these parts. The skirt or bottom portion of the piston structure 38 is connected to the disc 47 by the four webs 49 which may be considered as continuations of the webs 48. The 130 webs 49 are interrupted at the center in order to provide clearance space at 50 for the upper end of the connecting rod 14. This structure is shown more clearly in the section of Figure 3.

135 The head or working piston member 40 has a relatively thin central portion and at the margins the head is thicker in order to provide for the location of a piston ring groove 52. The groove 52 receives the piston ring 53, which may be a standard concentric ring having a step joint or 140 other suitable tight connection between the ends thereof, but which is preferably of the double stepped construction illustrated in Figure 16 and will be described in detail later. The ring 53 is narrower than the groove 52 by an amount of 145 approximately fifteen to twenty thousandths of an inch in the particular size of compressor mentioned above, this difference being exaggerated in Figures 6 and 7. The difference in width may be increased with an increase of the bore and 150

stroke. The groove 52 is of a depth great enough to provide a clearance back of the ring 53 as shown on an enlarged scale in Figures 6 and 7. This clearance is indicated at 54 in Figures 6 and 7 and it serves the dual function of clearance for the ring 53 and also as an inlet passageway for the working chamber 42, as clearly set forth in my copending application.

The upper and lower surfaces of the groove 52 are flat, that is, these surfaces are planes lying at right angles to the axis of the piston 40, so that they are parallel to each other. Likewise, the upper and lower surfaces of the ring 53 are parallel to each other and adapted to fit flat against the upper and lower end surfaces of the groove 52 and to form airtight contacts therewith.

The flanges 55 and 56 which define the end walls of the groove 52, or which are defined by the groove, are cylindrical and fit within the cylinder 46, namely, with a minimum clearance for the upper flange 55 and with a clearance of approximately fifteen to twenty thousandths of an inch for the lower flange 56. The reason for the greater clearance of the lower flange is to provide space between said flange and the cylinder wall to permit the entry of air into the working chamber 42 on the intake stroke of the compressor. That is to say, the space between the lower flange 56 and the cylinder wall 46 is a part of the intake passageway of the compressor. This does not need to be uniform all the way around. There might be shallow grooves across the end of the flange 56 instead of a uniform clearance.

A series of holes 57 are drilled in the upper surface of the piston head 40 in the flange 55, so as to intersect and communicate with the clearance 54 between the ring 53 and the groove 52. The ring 53 makes a tight fit with the cylinder 46. This fit is a peripheral, or cylindrical fit. The ring 53 also makes a tight fit with the flange 56 during the compression stroke by pressing against the same in an axial direction and making a flat or planar fit therewith. The ring 53 has sufficient friction with the walls of the cylinder 46 to cause it to tend to remain in any position in which it is placed in the cylinder bore, said ring fitting in the groove so freely that the piston tends to move with respect to the ring upon each reversal of motion of the piston. The piston and ring thus have lost motion between them to the extent of fifteen or twenty thousandths of an inch in the particular embodiment herein shown. This, obviously, may be greater or less, as may be desired.

As clearly disclosed in my copending application, the compression cylinder 46 is functionally disassociated from the guiding cylinder 2, although it is of the same diameter and structurally is rigidly connected to the same by virtue of the flange 62 of the working cylinder 46 being connected with the flange 60 formed at the upper end of the guiding cylinder 2 by means such as the cap screws 64. It is to be noted that the flange 60 is provided with a threaded opening 65 leading into the intake chamber 66 formed between the flanges 60 and 62. The chamber 66 communicates with the atmosphere through the opening 65. The upper end of the working cylinder 46 is provided with a discharge check valve chamber 68 which communicates with the interior of the cylinder 46 through the discharge passageway 44 mentioned above. The chamber 68 discharges through a cored passageway 69 and the communication between the cyl-

inder 46 and the discharge chamber 68 is controlled by a spring pressed check valve 73 in the form of a relatively thin disc of metal or other suitable material.

The operation of the structure thus far described is as follows: When the shaft 16 is turned, the crank and connecting rod will reciprocate the piston structure 38 in well known manner. As shown in Figure 1, the piston is at the bottom of its travel, the crank being in its lowermost throw. It will be observed that the ring 53 engages the top of the groove 52, that is, under the flange 55. The ring 53, having sufficient friction to drag along the cylinder walls, will be held by said friction of motion against the flange 55 during the downward stroke of the piston until the latter reaches the position shown in Figure 1. The position of the ring 53 at this time is best shown in Figure 7.

Now assume that the crank 16 is turned further, then the piston structure begins to rise. The ring 53 stands still, temporarily, but the piston rises, bringing the lower flange 56 against the ring 53 and, as soon as said lost motion—that is, the minute space between the ring and the end wall of the groove—has been taken up, the ring 53 is held against the lower flange 56 and is compelled to follow the upward motion of the piston, as shown in Figure 6. Thus the passage which was previously wide open is completely closed off in an exceedingly small part of the angular cycle of the crank shaft.

The ring 53, bearing against the lower flange 56 and simultaneously bearing against the inside of the cylinder wall 46, forms a fluid tight connection between the working piston 40 and the cylinder 46. The ring is held against said bottom end wall of the groove by two forces, first, the frictional resistance of the ring sliding along the cylinder walls 46 and, second, by the downward or outward pressure of the air compressed in the working chamber 42 by the upward stroke of the piston. In the present instance, since compressed air is admitted back of the ring 53, it tends to expand outwardly against the cylinder walls 46, as well as to be held downwardly against the flange 56, thereby securing an excellent seal between the piston and cylinder wall. So far as I know, this is broadly new.

As the piston travels upwardly the compressed gas is discharged past the valve 73 into the chamber 68 until the stroke is completed, whereupon the check valve 73 closes. The piston then starts on its downward travel. Whereas, on the upward stroke the position of the ring 53 with respect to its groove was as shown in Figure 6, as soon as the piston starts downward and moves a distance equal to the clearance between the ring and the end walls of the groove, the position of the parts relative to each other will then be as indicated in Figure 7. That is to say, the ring 53 will then engage the upper end wall of the groove 54, that is, against the flange 55, and will be drawn downwardly. In fact, the instant that the piston begins to move downwardly, the ring 53 leaves its lower seat, which is, in fact, the intake valve seat, and communication is thereupon opened between the working chamber 42 and the intake chamber 56, by a passageway of ample size to permit the flow of air into the working chamber 42 to occur freely.

The space radially between the flange 56 and the cylinder wall 46, while small in radial dimension, is relatively large in circumference and therefore permits of a relatively large total in-

80

take area to be secured. The intake passageway comprises the radial clearance 77 (Figure 7) between the flange 56 of the piston and the cylinder wall, the clearance 78 between the ring 53 in its upper position and the lower end wall of the groove 52, the clearance space 54 between the ring 53 and the bottom of the groove 52 and the drilled openings 57. The valve controlling this passageway is the packing ring 53, and it seats against the lower end wall of the groove 52 to close off said intake passageway.

When the compressor is operated at high speed the inertia of the ring acts to help the valve action, rather than to hinder it. Consider, for example, that the piston is moving inward on its compression stroke—that is, toward the cylinder head 45—and the stroke is being completed. The tendency of the inertia of the ring is to throw it ahead with respect to the piston 40. So long as the pressure of the gas upon the ring 53 exceeds the inertia of the ring, the ring will not tend to leave the valve seat. However, the tendency is there and operates in the right direction. Likewise, when the piston moves downwardly to the bottom of its suction stroke, the tendency is to throw the ring 53 downwardly against its seat, tending thereby to close the valve more quickly, so that the initial motion of the piston 40 will not be lost. This inertia tendency of the ring is relatively inconsequential in the size I have illustrated but it may, under certain circumstances, be important and I am calling attention to the same.

The clearance introduced by these minute intake passageways constitutes a very small fraction of the cylinder volume. The intake passageway, while it is of ample size, is exceedingly short. It is possible, of course, to further reduce the length of the intake passageway slightly by reducing the width of the ring 53, but the ring 53 should have sufficient bearing surface upon the inside of the cylinder wall, considering its diameter, to cause it to guide itself within the small limits of the clearance of the groove and the ring. The dome 43 of the piston 40 substantially fills the discharge passageway 44, thereby reducing the clearance at that point. I may employ a peripheral discharge check valve under certain circumstances, but I find the discharge check valve herein shown to be satisfactory. The rush of air through the intake passageway keeps metal particles, carbon and the like from depositing in the groove and thereby maintains the ring and the groove clear and in prime operating condition.

I have described above the pneumatic function of the packing ring, carried by the specially formed groove 52 in the piston 40, as a suitable intake valve. The piston is also provided with suitable lubrication carriers or wipers which serve a useful function in connection with the lubrication of the compressor.

The guiding cylinder 2 and the lower portion 39 of the piston are copiously lubricated by splash lubrication from the crank case. The piston structure 38 is so proportioned that the piston member or head 40, which is the working piston for the working cylinder 42, travels solely within said working chamber. Likewise, the guiding portion 39 of the piston structure operates solely within the guiding cylinder 2. The wiper, or lubricant distributor 47, however, works in both cylinders, namely, the cylinder 2 and the cylinder 46. While its chief function is to prevent the escape of lubricant from the crank case by form-

ing a seal over the guiding structure 39, it performs, also, the equally important function of transferring a minute quantity of lubricant from the guiding cylinder 2 to the working cylinder 46.

One of the greatest difficulties in air compression is with lubrication. The ordinary trunk piston of an air compressor must be lubricated sufficiently well to withstand the mechanical thrust and wear to which it is subjected as a machine element, independent of its pneumatic function. In the present piston construction I have separated the two functions, namely, the mechanical function and the pneumatic function, since the upper or working piston 40 has little or no guiding function in the cylinder 46 and the portion 39 has substantially no pneumatic function. It is, however, desirable to reduce the ring friction, that is, the friction between the ring 53 and the walls of the cylinder 46, and on that account it is desirable to provide a small amount of lubrication in the working cylinder.

About all the oil that is necessary in the working cylinder of this compressor is the equivalent of one or two drops an hour for lubricating the ring 53. Anything more than that is unnecessary and, in fact, detrimental, since it will be passed into the discharged compressed air. By holding the lubrication in the working compressor cylinder to a minimum, many advantages follow. First, the inlet passageway remains free of oil and the ring does not become gummed with carbonized oil in case of excessive temperature. Likewise, the oil does not accumulate on the discharge check valve and carbonize and cause the valve to leak. It also minimizes any danger of any possible explosion due to oil in the inter-cooler in the case of a compound compressor. There are numerous other advantages in sparse lubrication.

As an aid to the maintenance of sparse lubrication in the working or compressing cylinder the piston structure shown particularly in Figures 1 to 3 is provided with inclined walls or surfaces. The underside of the flange or wiper 47 is inclined or flared, see Figures 1 and 3, and the same is true of the upper marginal portion of the guiding crosshead 39 disposed just underneath the flange 47, being the portion of the piston structure adjacent where the arrow line 38 terminates in Figure 1. By virtue of this construction, in the upward movement of the piston 38 any oil deposited on this member from the guiding or lower cylinder 2 will be moved toward the central portion of the piston when the latter reaches its top dead center by virtue of the inertia of the oil, and on the downward stroke any oil that may be deposited on the underside of the ledge or flange 47 will be accordingly moved toward the center of the piston structure. There is thus a constant tendency to remove excess oil from the walls of the guiding cylinder and to direct the same toward the center of the piston structure from whence it returns to the crank case.

It is to be observed that not only does the compressing function and the mechanical driving function occur in parts of the compressor cylinder structure which are thermally separated, but also the same principles are utilized in constructing the piston. Actually, the piston construction embodies a compressing head or portion and a guiding portion.

The compressing piston 40 is thermally separated from the guiding piston 39 by a rigid connection comprising the relatively long, thin walls 48 which are freely in contact with the air in the intake chamber 66. The head 40 is com-

posed of a relatively thin wall, the bottom surface of which is freely in contact with the air which is constantly changed, due to the proximity of the intake passageway with the same, particularly at the beginning of the intake stroke. Thus the hottest air, namely, that immediately below the piston head 40, will be drawn into the cylinder at the beginning of the stroke and colder air will be drawn in towards the latter part of the stroke, with the result that there is a certain stratification and a consequent selective expulsion of the highly heated air at the beginning of the stroke, followed by the expulsion of the cooler air which is introduced into the working chamber 42 at the last part of the intake stroke.

Thus, not only is the highly heated air drawn away from the compressing piston 40, the piston part subjected to the high temperature, but also the walls 48 act as radiating fins and serve to dissipate heat from the compressing piston head 40. Due to this thermal separation of the parts, both as regards the cylinder construction and the piston construction, very satisfactory lubrication of the mechanical operating parts can be maintained under conditions where the compressors of the prior art would fail.

I do not intend to limit the piston structure and the associated inlet valve construction to that illustrated by way of example in Figures 6 and 7. In Figures 11 to 15, inclusive, I have shown different modified forms of piston head constructions to correspond to different forms of inlet valve rings. They do not exhaust by any means the variations which are possible within the principles taught herein.

In Figure 11 the ring 53 is provided with an upwardly extending flange 80 which is engaged by the upper flange 55 of the piston 40 on the downward stroke, the main body of the ring 53 being held away from the drilled passageways 57 during the intake stroke and the air entering by way of drilled passageways 82 under the ring 53, through the clearance between the bottom of the groove and the ring 53 and the space between the body of the ring 53 and the flange 55, and up through the drilled passageways 57. The drilled passageways 57 and 82 may be aligned, that is, formed by a through drilling. The action is the same as described in connection with Figures 6 and 7.

In Figure 12 I have shown the ring 53 as provided with a series of drilled passageways 84 which are obstructed by the lower flange 56 on the compression stroke, but the upper flange 55 of the piston is beveled, as at 55a, so that when the ring 53 is seated against the upper flange, as on the suction stroke, the passageways 84 are not obstructed. The inlet passageway in that case comprises the clearance between the flange 56 and the cylinder wall 46, the drilled passageways 84 and the clearance between the flange 55 and the cylinder wall 46. The operation is substantially the same as that described in connection with Figures 6 and 7.

In Figure 13 the ring 53 is provided with a series of diagonal drilled passageways 85, the lower ends of which passageways are obstructed by the lower flange 56 and the upper ends of such passageways 85 being not obstructed by the upper flange 55. The operation of this construction is substantially as described above in connection with Figures 6 and 7. In this construction it will be noted that the form of piston head is substantially the same as in Figure 12.

In Figure 14 the piston 40 is of somewhat dif-

ferent construction to accommodate a different form of valve ring. In Figure 14 the piston 40 is provided with the usual ring groove 52 to accommodate the main body of the valve ring 86 and, communicating with the groove 52, an auxiliary ring groove 52a is provided. This auxiliary groove accommodates a flat annular valve member 87 carried by the ring 86 and which serves to close, on the discharge stroke, the drilled passageways 88 but which does not obstruct at any time the drilled passageways 89 in the upper flange 55. Preferably, and as in Figure 11, the drilled passageways are aligned. This modification operates substantially the same as described in connection with Figures 6 and 7, it being noted, however, that the actual valve function is performed by the flat annular valve member 87 moved by the ring 86, instead of combining the two functions of valve and ring in the same structure. The ring 86 has a relatively slight lost motion with respect to the valve 87.

In Figure 15 I have illustrated a modified construction in which the upper flange 55 of the piston head 40 is considerably reduced and the ring groove 52 made somewhat more narrow. The lower flange 56 is, however, substantially the same form as is disclosed in Figures 12 and 13. In Figure 15 the ring 90 is not wholly contained within the groove 52 but has a flange 92 which is slotted, or notched, so as to provide, in effect, a series of projections from the ring 90 into the narrow groove 52 formed in the piston 40. The lower flange 56 cooperates with the ring 90 to seal the inlet passageways, that is, the space between the piston 40 and the cylinder wall 46, upon the upward or compression stroke. On the downward, or suction stroke, the projections 92 are caught by the upper flange 55 and air passes in between the flange 56 and the cylinder wall 46, under the ring 90 through the spaces between the projections 92, between the ring 90 and the adjacent wall of the head 40, and into the cylinder.

In view of the high speed of operation of the compressor herein shown it is desirable to stream line all constricted passageways and rapidly moving parts. For example, it is desirable to round off all sharp corners over which the air flows, to reduce the eddy currents and the friction of flow of the air.

Figure 16 illustrates the type of stepped joint, the valve rings 53, 86 and 90 are preferably provided with. In this figure the reference numeral 53 indicates the valve ring in its entirety and the abutting means thereof are complementarily formed in an identical manner. Each abutting end of the ring 53 is provided with a vertical portion 150 terminating in a projecting tongue 151 disposed in a plane arranged at right angles to the general plane of the portion 150. The portion of the ring 53 laterally opposite the portion 150 is provided with a slot 152 of substantially the same width and length as the projecting tongue 151. When the ring 53 is assembled on the piston head the portion 150 of one end overlaps the portion 150 of the other end and the tongue 151 at each end enters the corresponding slot 152 at the other end. Thus, the ring joint is in the nature of a double stepped construction in which the end portions of the ring overlap in abutting relation, both in a horizontal and vertical plane as well as in a perpendicular plane. In this manner lateral leakage at the ends of the piston ring is effectively prevented.

I have described above several different forms

of pistons in which the piston head was variously constructed to accommodate different forms of inlet valve rings. I will now describe a piston construction having a different form of wiper or oil distributor and, in addition, an oil control ring and groove therefor. In this case I remove, partly mechanically and partly pneumatically, any excess of oil from the guiding cylinder 2. At the same time I cool and ventilate the crank chamber. In this case the upper end of the guiding portion 39 of the piston structure 38 is provided with an oil control ring 115, set in a groove 116, this groove being of a greater width than the width of the ring, to provide a clearance 117 between the ring and the end walls of the groove. The groove communicates with a passageway 118 leading to the central open space 119 below the wall 120 of said guiding portion 39 of the piston structure. The ring 115 may be a standard concentric piston ring having the usual step joint, but preferably is of the double stepped construction illustrated in Figure 16 like the ring 53 and it operates as a check valve, like the ring 53. Due to the splash of the oil thrower, or dipper 33, the walls of the guiding cylinder 2 are copiously lubricated. As the piston rises from the position shown in Figure 9 to make the compression stroke, the natural tendency for the ring 115 is to lag, because of its frictional engagement with the walls of the guiding cylinder 2, behind the motion of the piston. The result is that the ring 115 engages the lower end wall of the groove, leaving the clearance 117 between the upper end wall of the groove and the ring 115. This provides, therefore, a passageway as follows, namely, from the space between the piston head 40 and the wall 120, through the clearance between the wall 120 and the cylinder walls of the guiding cylinder 2, clearance 117 between the ring and the groove and the radial clearance between the bottom of the groove and the back of the ring 115, passageway 118 to the open space 119, and thereby to the crank chamber.

As the piston rises there is thus a tendency to form a vacuum in the crank chamber and this I preferably arrange to augment by a tight crank chamber and the use of a check valve arranged to allow air to escape from the interior of the crank chamber but to prevent the entrance of air thereto. In Figure 1 I have shown the crank case and cylinder casting 1 as provided with a suitable check valve indicated in its entirety by the reference numeral 122, but it is to be understood that such a check valve construction need not be provided unless the piston structure indicated in Figures 8 and 9 is utilized in the compressor.

The operation of the structure so far described is substantially as follows: As the ring 115 moves upwardly in the guiding cylinder 2 it tends to scrape lubricant off the walls of the guiding cylinder 2 and the same is then drawn through the aforementioned passageway into the crank chamber. The scraping from the walls is mechanical and the removal of the excess lubricant thus scraped is pneumatic.

When the piston has reached the top of its stroke the ring 115 seizes the walls with whatever friction it has, and as the piston descends the ring lags behind and engages the upper end wall of the groove 116, closing off communication between the bottom of the wall 120 and the top thereof. Any oil which is not scraped from the walls by the ring 115 cannot be driven upwardly, as is the tendency in compressors as heretofore

constructed, for two reasons. First, the ring 115 prevents discharge past the same by such pneumatic pressure as is created in the crank chamber and second, I preferably make provision for releasing such pressure as might be generated in the crank chamber through the provision of the automatic check valve 122 aforementioned, for complete details of which reference may be made to my copending application mentioned above.

It is to be observed that atmospheric pressure prevails in the space between the head 40 and the intervening head 120, so that the formation of a reduced area of pressure within the crank case does not affect the pneumatic action of the working head or piston 40 in its working cylinder 46. While this is the desirable and preferred construction I wish it to be understood that this phase of the invention is applicable to compressors where the intake port extends through the walls of the cylinder itself and to a construction which does not interpose atmospheric pressure between the guiding portion of the cylinder and the working, or pneumatic head of the piston.

Lubrication of the working cylinder 46 in this case is effected by a series of projections 123 on the webs 48 carried by the piston 38. These projections contact alternately with both cylinders and serve to carry across the gap between the cylinders sufficient lubrication to keep the ring 53 in the cylinder 46 sufficiently lubricated for satisfactory operation. As the piston descends there is a tendency to compress the air in the crank case and to force the same out past the valve 122. At that time the projections 123, which have a very slight clearance, possibly fifteen thousandths of an inch on one side, in the bore of the guiding cylinder 2, descend into the guiding cylinder and contact with the oil on the walls of the cylinder. As the piston thereafter rises, the ring 115, engaging the lower end of its groove, opens a passageway for permitting air and the oil which is scraped from the walls of the guiding cylinder 2, to be drawn down into the crank chamber as the piston rises. At the same time, the projections 123 of the piston 40 transfer a film of oil to the walls of the compression cylinder 46, providing sufficient lubrication therefor.

While I have shown and described above certain novel details relative to the guiding piston and the thermally separate compressing piston, the various forms of piston heads arranged to cooperate and accommodate the various forms of valve rings, and the means carried by the piston structure for securing the proper lubrication, it is to be understood that my invention is not to be limited to the specific means shown and described, but that, in fact, widely different means may be employed in the practice of the broader aspects of my invention.

What I claim, therefore, and desire to secure by Letters Patent is:

1. A piston structure comprising a cylindrical crosshead portion and a piston portion of substantially the same diameter, said piston and crosshead being connected rigidly by integral webs, and an oil transfer member carried by said connection.

2. A piston structure comprising a cylindrical crosshead portion and a piston portion of substantially the same diameter, a ring for each portion, each portion having an air passageway controlled by its ring respectively.

3. A piston structure comprising a cylindrical crosshead portion and a piston portion of sub-

stantially the same diameter, said piston and crosshead being connected rigidly by integral webs, an oil transfer member carried by said connection, and means adapted to dissipate heat connecting the piston portion with said crosshead portion.

4. A piston structure comprising a crosshead portion, a piston portion of substantially the same diameter as said crosshead portion, said piston portion having a groove therein and an intake passageway, and a piston ring controlling the opening and closing of said intake passageway.

5. A piston structure comprising a piston head having a pair of spaced flange members, and a piston ring member disposed between said flange members and movable to two positions therebetween, one of said members having openings formed therein and extending in a generally axial direction relative to the piston head, said openings being entirely closed off by movement of the ring member to one of its positions.

6. A piston structure comprising a piston head having a pair of spaced flange members, and a piston ring member disposed between said flange members and movable to two positions therebetween, said ring member having openings formed therein and extending in a generally axial direction relative to the piston head, said openings being entirely closed off by movement of the ring member to one of its positions.

7. A piston structure comprising a piston head having a pair of spaced flanges disposed in parallel relation, one of said flanges having bores therein extending in a generally axial direction, and a piston ring disposed between said flanges and movable to two positions therein, one entirely closing off at least certain of said bores.

8. A piston structure comprising a piston head having a pair of spaced flanges, the lower of said flanges having bores therein extending in a generally axial direction, and a piston ring disposed between said flanges and movable to two positions therein, one entirely closing off the bores in said lower flange.

9. A piston structure comprising a piston head having a pair of spaced flanges of unequal diameter, the upper flange being of larger diameter and having bores therethrough extending in a substantially axial direction relative to the piston head, and a piston ring disposed between said flanges and movable to two positions therein, one against the lower flange of smaller diameter to close off communication through said bores from the space above the piston head to the space below.

10. A piston structure comprising a crosshead portion, a piston portion including a head wall having a pair of spaced flanges, a piston ring therein, webs joining the crosshead and piston portions, and oil transferring means carried by said webs between said crosshead and piston portions.

11. A piston structure for use in cylinders and the like and comprising a crosshead portion, a piston portion, webs joining the crosshead and piston portions, and cylinder contacting means carried by said webs between said crosshead and piston portions and adapted to transfer lubricant from one cylinder surface to another.

12. A piston comprising a head having a relatively thin wall and a short cylindrical skirt, said skirt having a peripheral ring groove with planar radially extending walls, and a ring of less width than the groove disposed in said

groove, the groove providing clearance back of the ring communicating with the clearance between the ring and the end walls of the groove and open communication being provided between the clearance back of the ring and the top of the piston.

13. A piston structure comprising a head having a relatively thin wall and a short cylindrical skirt, said skirt having a peripheral ring groove therein, a ring valve disposed in said groove, a guiding crosshead of somewhat greater diameter than said piston head, a crossed web structure connecting the piston head with said crosshead, and projections formed on said web structure and adapted to contact with the portion of the cylinder engaged by the crosshead and also with the portion of the cylinder engaged by said ring valve.

14. A piston structure comprising a cylindrical crosshead portion adapted to operate in one part of a cylinder and a piston head portion adapted to operate in another portion of the cylinder, integral webs connecting said piston head portion with said crosshead portion, and a flange supported between said portions and provided with an edge adapted to wipe oil from the portion of the cylinder engaged by said crosshead portion.

15. A piston structure comprising a cylindrical crosshead portion and a piston head portion, said piston head portion having a relatively thin wall and a short cylindrical skirt with a peripheral ring groove therein, a ring valve disposed in said groove, integral webs joining said piston head portion with said crosshead portion, oil transfer means carried by said webs, and an oil scraping ring carried by said crosshead portion.

16. A piston structure comprising a cylindrical crosshead portion and a piston head portion joined together by integral webs arranged to prevent the excessive transfer of heat from the piston head portion to the crosshead portion, there being a transverse bore in said crosshead portion, and a wrist-pin disposed therein, said webs being interrupted adjacent said wrist-pin to accommodate a cooperating connecting rod.

17. A piston structure comprising a cylindrical crosshead portion and a piston head portion, means comprising integral heat dissipating webs joining said crosshead portion and said piston head portion, there being a groove formed in each of said portions, and a ring valve disposed in each of said grooves.

18. A piston structure adapted for operation within the walls of a cylinder, said piston structure comprising a lower skirt portion terminating in a head portion having a peripherally flared surface inclined away from the cylinder walls and a connected flange spaced therefrom and provided with an undersurface also flared and inclined away from the walls of the cylinder.

19. A piston structure comprising a cylindrical crosshead portion having at its upper end flared walls inclined toward the axial center of the piston and away from the walls of the cylinder, and a separated flanged portion carried on the crosshead portion by integral webs, said flanged portion being also provided with a flared surface inclined toward the center of the piston and away from the walls of the cylinder, whereby any oil deposited on said flared walls will by their inertia be directed toward the center of the piston when the latter changes its direction of movement.
